BRUSH FOR VENETIAN BLINDS

Sam Zbarsky, Brooklyn, N. Y.

Application December 7, 1937, Serial No. 178,478

1. Claim. (Cl. 15—210)

This invention relates to brushes, more particularly, to a type of brush which is essentially adapted for the cleaning of Venetian blinds and the like.

As can be easily realized, the cleaning of Venetian blinds is a difficult and tedious matter, particularly with the ordinary type of brush wherein it is possible only to clean a single slat at a time. It therefore becomes highly desirable to provide a brush which is capable of cleaning a plurality of slats simultaneously. Since Venetian blinds vary in size, that is, in the spacing between the slats, it is highly desirable that a brush for this purpose be capable of not only cleaning a plurality of slats, but that it be adjustable in order to provide for the different sizes of Venetian blinds encountered on the market.

Prior brushes, such as are well known in the art, are not adapted for this purpose. For example, there has been on the market a brush consisting of a plurality of brushing members threaded into a holder, but these brushes are of such a character as not to lend themselves for the purpose of cleaning Venetian blinds because each of the members consists of a series of bristles, and the manner in which such bristles align themselves would make it almost impossible to successfully and effectively clean Venetian blinds.

In accordance with the present invention, I provide a brush holder consisting usually of an elongated wooden member. Said member has generally two sets of equally spaced openings adapted to temporarily receive brushing members. Each of said members consists of a core having cemented, or otherwise secured thereto, lambskin or other animal skins to form the brushing members. Said members are mounted in the holder, being equally spaced and being parallel to each other. The parallel relationship of the brushing members throughout practically their entire length is an important feature of a brush of the type described herein.

In order to facilitate the introduction of the brushing members into the holder, and also to firmly secure them in their position, I provide a special construction involving the use of nuts which are secured in the holder and corresponding threaded members extending from the brushing members for threading the same in place.

In the accompanying drawing, constituting a part hereof, and in which like reference characters indicate like parts,

Fig. 1 is a side elevational view of a brush made in accordance with my invention, showing some

of the brushing members in full and others in outline;

Fig. 2 is a vertical, cross-sectional view taken along the line 2—2 of Fig. 1; and

Fig. 3 is a view from below showing the arrangement of two sets of equally spaced openings.

The device consists essentially of an elongated holder 1 having a handle 2 secured to the top thereof by dowel pins 3 or the like. It will be noted from Fig. 1 that the handle is at a substantial angle to holder 1 and the plane of handle 2 is within the plane of the brushing members.

A slot or groove 4 is formed along one side of holder 1 throughout substantially its entire length. Said groove, as best shown in Fig. 2, is relatively deep and extends beyond the center line of the holder. A series of openings 5, 6, 7, 8, 9 and 10, equally spaced, extend from the lower side of holder 1 through the groove 4 and a substantial distance into the body of the holder. A second set of openings of similar character, best shown in Fig. 3, as openings 11, 12 and 13, are equally spaced with respect to openings 5 and 10 and with respect to each other. A brushing member is adapted to be held in each of said openings. If a Venetian blind having a relatively wide spacing between slats is to be cleaned, then the brushing elements are inserted into openings 5, 11, 12, 13 and 10. If, on the other hand, a Venetian blind with relatively narrow spacing between slats is to be cleaned, the brushing elements are inserted into openings 5 through 10, inclusive. In each case, the brushing members are equally spaced from each other.

Each of the brushing elements consists of a core 14 usually of wood, having a covering 15 of lambskin or the like cemented to the core 14. In the free end of the core 14 is a wood screw 16 having a portion 17 projecting from the end of said core and provided with threads. A series of nuts 18 are inserted in groove 4 and are positioned with the openings of said nuts in alignment with the several openings 5 to 13, inclusive. Usually, the width of the groove 4 is such that the nuts 18 are held firmly in position. A strip 19 is introduced into the groove 4 and is held in place by cementing or otherwise.

From the above description it will be apparent that the brush of the present invention is simple to construct and effective in action. There are provided a plurality of brushing members 15 which may be spaced in various ways, as desired, which are always parallel to each other, and which may therefore be effectively used for a rapid cleaning of Venetian blinds. The handle 2

is at such an angle as to make the brush easy to hold and simple to manipulate without undue strain on the operator.

I am aware that it has previously been proposed to form brushing elements with a wooden core having a threaded member on the end thereof. However, such cores were conical in nature and had a threaded member as part of the core itself. This is unsatisfactory in that the threaded wooden portion, being relatively fragile, easily broke. Furthermore, in such construction, a series of bristles were formed around the core which flared outwardly and which were capable of exerting a brushing effect only on the end and not on the sides thereof.

I am also aware of a proposed construction of a brush in which the brushing element consisted of a set of bristles having a piece of wire or the like spirally wrapped around the end thereof in such a manner as to form a threaded end. Said end was intended to be introduced into a similarly threaded holder. However, this was quite unsatisfactory because it was almost impossible to correctly space the convolutions of the wire and it was difficult to cause the wire to hold the bristles in place. Furthermore, in use, the wire was apt to be displaced, making it impossible to insert the brushing element into the holder.

Although I have described my invention setting forth a single embodiment thereof, it is quite apparent that various changes may be made in the details of construction of brushes within the scope of my invention. For example, instead of lambskin, other animal skins may be used or brushing elements may be formed in other ways,

it being essential that there be a core and that the brushing elements be parallel to each other. In the specific example, I have described two sets of equally spaced openings having five and six openings, respectively, in said sets. The exact number of openings is not of importance and, therefore, the number of openings in each set may be varied. If desired, more than two sets of openings may be provided. The groove may be varied considerably in its characteristics, as, for example, I may form a series of small grooves, each of which is capable of holding one or more of the nuts. In place of the strip 19, I may introduce plastic material which will harden in place and hold the nuts in their proper relation. Instead of the materials shown and described, other materials adapted for the purpose may be substituted. These and other changes in the details of construction of the present invention may be made, and the invention is not to be limited except by the character of the claim appended hereto.

What I claim is:

A brush comprising an elongated holder, a series of openings along one side thereof, said series including two sets of equally spaced openings with the end openings common to both sets, a plurality of substantially parallel brushing members adapted to be inserted in said openings, a core for each of said members, a brushing element secured around said core, a threaded member held centrally within and projecting from one end of said core and a nut in each of said openings into which said threaded member is adapted to be held.

SAM ZBARSKY.
